US00D682251S

(12) **United States Design Patent**
Behringer et al.

(10) **Patent No.:** US D682,251 S
(45) **Date of Patent:** ** May 14, 2013

(54) **AUDIO COMPONENT WITH MAIN
CONTROL KNOB**

D608,341 S * 1/2010 Nakagawa D14/198
D625,279 S * 10/2010 Boudreau et al. D14/137
D644,623 S * 9/2011 Behringer et al. D14/188

(75) Inventors: **Ulrich Behringer**, Makati (PH); **Costa
Lakoumentas**, Surrey (CA); **David
Czarnecki**, Seattle, WA (US)

* cited by examiner

(73) Assignee: **Red Chip Company Ltd.**, Tortola (VG)

Primary Examiner — Keli L Hill

(**) Term: **14 Years**

(74) *Attorney, Agent, or Firm* — Seed IP Law Group PLLC

(21) Appl. No.: **29/363,140**

(57) **CLAIM**

(22) Filed: **Jun. 4, 2010**

The ornamental design for the audio component with main
control knob, as shown and described.

(51) **LOC (9) Cl.** **14-03**

DESCRIPTION

(52) **U.S. Cl.**

USPC **D14/188**

(58) **Field of Classification Search** D14/162,
D14/167–169, 175, 179, 188, 194–198, 215,
D14/217, 257, 258, 265, 299, 496; D13/163,
D13/164; 84/625, 660, 697; 455/344–351;
330/1 R, 3, 4, 250; 381/86, 120

FIG. 1 is a perspective view of the audio component with
main control knob showing the new design.

See application file for complete search history.

FIG. 2 is a top plan view of the audio component with main
control knob of FIG. 1.

(56) **References Cited**

FIG. 3 is a front elevational view of the audio component with
main control knob of FIG. 1.

U.S. PATENT DOCUMENTS

FIG. 4 is a bottom plan view of the audio component with
main control knob of FIG. 1.

D331,406 S * 12/1992 Goatman D14/137
D454,110 S * 3/2002 Andre et al. D13/110

FIG. 5 is a back elevational view of the audio component with
main control knob of FIG. 1.

FIG. 6 is a right-side elevational view of the audio component
with main control knob of FIG. 1; and,

FIG. 7 is a left-side elevational view of the audio component
with main control knob of FIG. 1.

The broken lines shown are included for the purpose of illus-
trating the unclaimed portions of the article and form no part
of the claim.
